Specification of Letters Patent.

Patented Aug. 5, 1919.

Application filed November 23, 1917. Serial No. 203,551.

To all whom it may concern:

Be it known that I, RENÉ HANRIOT, a citizen of the French Republic, residing at 32 Avenue du Roule, Neuilly-sur-Seine, in the 5 Department of Seine, France, and I, FERNAND GRATIEUX, a citizen of the French Republic, residing at 14 Rue Oberkampf, Paris, in the Department of Seine, France, have invented a new and useful Improvement 10 in Aeroplanes, of which the following is a specification.

The present invention relates to a control mechanism for the ascent or descent rudder or elevator of aeroplanes, arranged under 15 such conditions that all the organs of this apparatus are placed in the interior of the fuselage.

This mechanism is illustrated in the accompanying drawing in elevation.

20 In this drawing *a* indicates the elevator which has to turn upon a horizontal axis at right angle to the direction of the apparatus. This motion is controlled as follows.

The control lever *b*, operated by the pilot 25 oscillates about a fixed point *c*. On both sides of this point of oscillation there are attached to this lever at *e* and at *d* on the one hand the cables *f*—*f*, and on the other hand *g*—*g*. These cables extend the length 30 of the fuselage, suitably guided or conveyed by pulleys or other convenient arrangements, and are attached to the correspondings ends *i* and *j* of a rod *h* placed at the rear of the said fuselage, in the middle plane 35 of the apparatus. The cables, *f*, *g* rod *h* and the part of the lever *b* included between *d* and *e* form the sides of a parallelogram.

At the upper end of the rod *h* there is articulated an adjustable coupling rod *k* formed of a steel tube, which rod is connected with a lever *l* fixed upon the rudder *a* at the middle of the horizontal tube *m* which possesses the articulations.

40 This mechanism has been devised for the purpose of placing the controlling parts in the interior of the fuselage and thus avoiding all passive resistance.

What we claim is:—

In combination with an aeroplane elevator 50 a control mechanism comprising a control lever pivoted near its lower end on the aeroplane frame, cables attached to said control lever respectively above and below the said pivot and extending the length of the fuselage, a vertical rod at the rear of the fuselage 55 pivoted at its center to the frame in its longitudinal axial plane, and having the aforesaid cables attached to its upper and to its lower end respectively, and an adjustable connecting tube attached at its front end to one end of the aforesaid vertical rod and at 60 its rear end to a lever keyed on the rotatable axles of the aeroplane elevator.

In testimony whereof we sign our names to this specification in the presence of two 65 subscribing witnesses.

RENÉ HANRIOT.
FERNAND GRATIEUX.

Witnesses:

HENRI BLOUIN,
CHAS. P. PRESSLY.
